UNITED STATES PATENT OFFICE.

MAXIMILIAN CHARLES SCHWEINERT, OF WEST HOBOKEN, AND JULIUS VOLCKHAUSEN, OF WEEHAWKEN, NEW JERSEY.

TIRE-VALVE.

1,216,853.

Specification of Letters Patent. Patented Feb. 20, 1917.

Application filed September 8, 1911. Serial No. 648,359.

To all whom it may concern:

Be it known that we, MAXIMILIAN CHARLES SCHWEINERT and JULIUS VOLCKHAUSEN, both citizens of the United States, residing 5 in West Hoboken, county of Hudson, and State of New Jersey, and Weehawken, county of Hudson, New Jersey, respectively, have invented certain new and useful Improvements in Tire-Valves, of which the 10 following is a specification.

This invention relates to tire valves and aims to provide certain improvements therein.

The invention is specially directed to that 15 type of valve in which the valve proper is in the foot of the valve shell, and means are provided for depressing the valve to hold it in its open position during the act of deflating. It has been proposed to utilize for this 20 purpose an inflating tube which extends through the valve shell which is provided at its outer end with means for engaging a pump tube or other inflating tube. Air is forced through the inflating tube into the 25 valve shell, and against the valve, whereby to open it. Such valves have also been provided with an exterior collar engaging the inflating tube and adapted to force the same downwardly to unseat the valve, and to raise 30 it upwardly to permit the valve to become seated during the act of inflation and during running of the vehicle. Valves of this type, however, have been found to leak during the 35 inflating operation, the air passing through the end of the inflating tube outwardly between the tube and the shell. It is one of the objects of the present invention to improve this type of valve so as to prevent leakage. The invention also includes cer- 40 tain other features which will be hereinafter referred to.

In the drawing, which illustrates several embodiments of the invention,

Figure 1 is a diametrical section, partly 45 in elevation of a valve of the type referred to showing the inflating tube raised.

Fig. 2 is a similar view showing the valve depressed and in its open position.

Fig. 3 is a top view of the valve.

Fig. 4 is a section taken on the line 4-4 in 50 Fig. 1.

Fig. 5 is a bottom view of the lower end of the inflating tube.

Figs. 6 and 7 are modified forms of the inflating tube.

Figs. 8 and 9 are modified forms of packing for the inflating tube.

Figs. 10, 11, 12 are modified forms of valve proper.

Referring first to Figs. 1 to 5, let *a* indicate a valve shell having an enlarged foot *b* formed with a valve seat *c*. The valve proper is usually in the form of a disk *d* having a packing washer *e* designed to contact with the valve seat *c*, and which may be 60 retained in place and be prevented from adhering to seat *c* by suitable means, as for instance a shoulder formed by an entering recess *c*² in disk *d* and a flange *c*³ at the outer edge of the disk. The valve proper may be 65 provided with a recess *f* partly inclosing a coiled spring *g*, the lower end of which may be seated upon a circular projection *h* carried in a circular casing *i* which is adapted to screw upon the valve foot, as shown. 70

The lower wall of the casing is formed with a passage or passages *j* through which the air escapes into the tire.

Movably mounted within the valve casing is an inflating tube *k* which is shown as 80 formed in two parts screwed together, and the upper end of which is shown as formed with a screw-thread *l* on its exterior. The upper end of the casing *a* is also screw-threaded at *m*, the threads *l* and *m* being of 85 reverse pitch. A screw-threaded collar *n* is provided which engages both the threads *l* and *m*, so that as the collar is rotated in one direction the inflating tube *k* is raised or drawn away from the valve *d*, while when 90 the collar is rotated in the opposite direction, the inflating tube is moved inwardly to depress the valve and hold it in its open position. To prevent rotation of the tube the latter may be provided with a groove *x* into 95 which fits a projection *x*' on a casing. During the act of deflation the lower end of the tube seats on the top of the valve *d*, and in order to provide a free passage into the tube *k* for the air which escapes outwardly 100 around the valve, the lower end of the tube is slotted or provided with passages *o* as shown.

As the tube *k* is drawn outwardly away from valve *d* in order to permit the latter to 105 close during the act of inflation, it is found

that air passing inwardly through the tube leaks outwardly between the tube and the casing so as to render it difficult to inflate the tire. As the pressure in the tire is increased the valve d seats more firmly and requires a heavier pressure to unseat it. Hence as the pressure is increased the leakage around the tube is also increased.

Our invention provides a means for preventing such leakage. It is usual to provide some means for limiting the upward movement of the tube k such as coacting shoulders p p' formed upon the tube and casing. In adjusting the tube from its lowermost position to its uppermost position, it may occupy any one of a number of different positions, unless care is taken to move it to its extreme upward limit. Our invention in its preferred form comprises a means for preventing leakage around the tube in any position which it may assume. To this end we provide what is in effect a piston packing q which may consist of the cupped leather washer shown, or any other suitable device capable of making a tight joint between the parts, and at the same time permitting their relative movement. When the tube k is formed in two parts as shown, the piston packing may be conveniently applied at the joint between the parts, being held in place by threading the parts together. Preferably a metal washer r is interposed beneath the packing as shown. The washer q thus described also constitutes an efficient packing between the several parts of the tube, thus preventing leakage at this point.

According to our invention it is not necessary that the inflating tube shall extend entirely through the bore of the valve shell to the valve proper. In Fig. 6 we have shown one form of the invention in which the valve proper d' is provided with a rod a' fixed to its upper end, which is adapted to be engaged by a short tube b' mounted at the outer end of the valve shell. The tube b' is provided with projections c' c' which work in slots e' e' formed in the valve shell, while movements of the tube are effected by a coupling sleeve f' engaging screw threads upon the tube b' and the shell. The tube is provided at its lower end with a packing g' which is designed to form a tight joint with the wall of the bore of the valve shell as shown, so that air cannot leak around between the tube and the shell.

In Fig. 7 a somewhat similar construction is shown. In this figure a coupling sleeve h' is swiveled to a flange i' formed on the inflating tube j' , and engages threads formed on the upper end of the valve shell. The inflating tube carries a packing k' which in this instance is shown as seating against a shoulder or seat l' formed on the

shell. The packing is held in place by a washer m' . The washer and packing are preferably inserted through the bottom of the valve. To this end the washer may be provided with projections to engage a tool by which it may be rotated.

In Fig. 8 the construction of Fig. 1 is modified to the extent that a recess o' is provided in the valve shell, which receives a packing washer p^2 which makes a tight fit with the tube k . Under pressure the packing is crowded not only against the shoulder of the recess o' but against the wall of the tube. The fit between the parts may be quite tight in this construction, since the tube is moved by hand and not by air pressure.

In Fig. 9 a somewhat similar construction is adopted, except that the packing washer q' is carried upon a reduced portion of the inflating tube k and is adapted to make contact with the conical seat r' when the tube is screwed upwardly.

The valve proper is not necessarily limited to the construction illustrated in Fig. 1. It may embody other means for holding the packing washer in place.

In Fig. 10 another means of accomplishing this result is shown. Here the valve disk which is designated d^{20} is threaded at d^{21} and receives a correspondingly threaded ring d^{22} which is screwed down upon the inner edge of washer e and holds the inner edge thereof. The outer edge is held by a flanged ring d^{23} which is threaded and screwed upon the threaded periphery of the disk.

In Fig. 11 the disk d^{20} receives a pin d^{24} which passes through its upper part and overlies ring d^{22} which it holds in place upon washer e . The outer edge of the washer is retained by ring d^{23} the lower edge of which is flanged over the disk and the upper edge over the washer.

In Figs. 6, 8, 9 and 12 the footing b^{40} is illustrated as formed integral with the valve shell a instead of being formed separately as in Fig. 1. A modified arrangement of valve is also illustrated in Fig. 12 whereby the washer e^{40} is seated in an annular recess c^{40} on the bottom of footing b^{40} and against which the upturned end d^{41} of the disk d^{40} is seated. The washer e^{40} may be retained in place if desired by flange a^{40} on the bottom of shell a .

While we have described in detail certain forms of the invention, it is understood that we do not wish to be limited to the form shown, since various changes can be made therein without departing from the invention.

We claim as our invention:

In a tire valve or the like, the combination of a valve shell, a valve proper carried by said shell, an inflating tube separate

from said valve proper and movable in said shell, and a packing for making a tight joint between said inflating tube and said shell, said tube being made in two parts 5 and adapted to clamp said packing between said parts.

In witness whereof, we have hereunto

signed our names in the presence of two subscribing witnesses.

MAXIMILIAN CHARLES SCHWEINERT.

JULIUS VOLCKHAUSEN.
